JOSEF EINAR THURESON, OF STOCKHOLM, SWEDEN, ASSIGNOR TO NYA AKTIEBOLAGET
GALCO, OF STOCKHOLM, SWEDEN, A JOINT-STOCK COMPANY

LOOSE-LEAF BINDER, CARD-SYSTEM FILE, OR THE LIKE

Application filed June 1, 1929, Serial No. 367,648, and in Sweden October 4, 1927.

The present invention refers to letter covers, card system files, loose-leaf binders or the like, preferably of the type in which a back frame provided with attachments for the leaves is composed of two half-parts pivotally connected with each other, said half-parts being each hinged to one of two fillets or the like of sheet-metal extending along the outer edges of the back of the binder, said fillets serving as attachments for the side portions of the covers. These fillets are called cover attachments hereinbelow.

The accompanying drawings illustrate an embodiment according to the invention as applied to so-called card system binders, in which the back-halves may be displaced in relation to each other in the longitudinal direction of the back when the back-halves have been opened.

Figs. 1 and 2 show the back of the binder including the cover attachments in closed positions and viewed from within and from the end respectively. Fig. 3 shows the same in open position viewed from within and with the back halves displaced relatively to each other in the longitudinal direction. Fig. 4 is a fragmentary side elevation. Fig. 5 shows the back of the binder in closed position and viewed from the end, with one cover attachment occupying the closed position while the other cover attachment is opened. Fig. 6 shows the right portion of Fig. 5 to an enlarged scale, and Fig. 7 illustrates the left portion of Fig. 5 to an enlarged scale and partly in section.

Card system binders of the type shown in the drawing are intended to receive a number of series of cards of a height considerably less than that of the binder, each such series being situated between two leaves of about the same height as the binder, and the cards of each particular series being superimposed in such a manner that the uppermost portion of an underlying card is not covered by a card lying thereon.

By the feature that the back halves may be displaced in the longitudinal direction relatively to each other, as stated hereinbefore, one or more leaves of the same series may be readily moved from a lower to a

higher position or vice versa, without the necessity of first detaching the same. Such displacement of the leaves takes place, for instance, when a new card is to be inserted between two cards already inserted. The back members are moved to the open position and then displaced relatively in a longitudinal direction. Cards carried on either set of prongs may be moved to the other set of prongs, then when the back members are returned to their original position, the cards which have been moved from one set of prongs to the other are displaced longitudinally with respect to their original position. If new cards are to be inserted, their position longitudinally with respect to the cards already in the binder may be determined by placing them on one or the other of the sets of prongs.

When it is desired to effect recording on the cards or leaves, it is preferable that the back halves occupy a half-opened position, in that the cards or leaves in the binder are not then pressed hard against each other, but are loose so as to lie flat when the binder is opened, even if the latter should happen to be fully occupied by cards inserted therein.

With the construction of the locking means for keeping the back halves in the closed and in the half-opened position as hitherto used, the disadvantage is involved that on the release of the spring-actuated latch, which is understood to take place after the binder has first been opened, the back halves will immediately open altogether under the pressure of the two halves of the opened binder, if the tendency of the back halves to assume the fully open position is not checked by a special manipulation.

The present invention comprises means for obviating this drawback, and this means is principally characterized by the feature that the latching device is provided with a guiding means which is rendered operative by the opening movement of the back halves, in such a manner as to bring the latching members into engagement, corresponding to the half-opened position.

The two back-halves 1 and 2, which are here conceived as made from steel plate, are

provided at their adjacent edges with hinge members 4 and 5 respectively, which engage between each other and have a hinge pin 3 extending therethrough in known manner.

5 The length of these hinge members or hinge sleeves 4 and 5 is so adapted that free spaces 26 are formed between adjacent sleeves in such manner that the two back-halves may be displaced relatively to each other along the pin 3 a distance equal to the distance between the prongs 7 of the one back-half and the adjacent prongs of the other back-half, that is to say, the distance between the prongs of a pair of prongs or 10 the distance between the holes of a pair of holes in the cards.

15 17 designates the cover sides which are carried by cover attachments 15 secured between the sides of the back halves 1, 2, and the 20 prong attachments 8.

25 The prong attachment of the one back-half is provided with a support having two branches 21 directed toward the other back-half, and the prong attachment of the other back-half is provided with a corresponding support 22 having its branches directed toward the branches of the support 21. The supports which are preferably made integral with the appertaining prong attachments are 30 bent at their free ends.

In the closed position of the back these branches bear or nearly bear against each other, as will be seen from Figs. 1 and 5.

35 In the inside of each support 22 a latch 11 is pivotally secured by means of a pin 12. This latch is provided on one side only with two locking lugs 30 and 31.

40 When the back of the binder is closed, each latch 11 enters a recess 34 in a bent end of the support 21.

45 When the back is entirely closed (Fig. 1) the locking lug 31 is brought into engagement inside the edge of the recess, whereas when the back is in half-opened position the locking lug 30 is in engagement with the said edge.

50 A trigger 13 in the form of a pivoted lever is connected by means of a wire 14 with the lower latch 11, and moreover the two latches are interconnected by means of a wire 27 while being each under the influence of a spring 28 which tends to move the latch into the locking position. As will be readily seen from the drawing and from the description hereinbefore, the arrangement is such that if 55 the back-halves are interlocked and the trigger is actuated against the pressure of the springs, the latches will be released from their engagement with the edge of the recess 34.

60 In order that the latches shall not be brought out of engagement with the supports 21 altogether on a preliminary actuation of the trigger 13, that is to say, in order that the back shall not be entirely opened, but remain 65 in the half-opened position and be locked in

the same by the locking lugs 30 being caused to bear on the inside of the edge of the slots 34, each latch is provided with a projection 32 on that edge which is opposite to the edge on which the locking lugs 30 and 31 are provided. This projection 32 is moreover arranged at a somewhat greater distance from the free end of the latch than the lug 30, but not so far therefrom as the lug 31. Furthermore, the distance between the base of the lug 30 and the point of the projection 32 should be about equal to the extension of the recess 34 in the direction of movement of the latch, that is to say in the longitudinal direction of the back of the binder.

back-halves into the position according to Fig. 3.

15 denotes the two cover attachments, each of which is pivotally connected to the front edge of one of the two back parts. Each such cover attachment 15 consists of a fillet, bar or the like of sheet-metal of the same length as the back-halves, and each fillet is provided at both ends with a bent edge or flange 9 situated in the same transversal plane as the similar flanges 6 on the back-halves 1 and 2. The rear portion of each cover 17 bears on the inside of the appertaining cover attachment 15, and the edges 9 form abutments for the end portions of the cover. Lugs 16 cut out of the cover attachment unite the cover and the cover attachment. The connection between each back-half and the appertaining cover attachment consists of a hinge, hinge members 18 rigidly connected with the back-half entering between hinge members 19 which are made integral with the cover attachment, besides which all members 18, 19 have a hinge pin 20 extending therethrough.

25 The hinge members 18 are connected with the back-half by means of the same lugs 10 which connect the back-half with the prong attachment, the said members 18 being made integral with pieces of sheet-metal 41 situated between the back-half and the prong attachment. The prong attachment and the back-half are kept at a suitable mutual distance by lugs 42 of suitable length on the sheet-metal pieces 41, the said lugs 42 bearing on the outside of the prong attachments 8.

40 The portion 40 adjacent to the hinge members is shaped in such a manner as to form a longitudinal recess or groove on the outside of the cover attachment and a corresponding elevation, ridge or the like on the inside of the cover attachment.

45 This arrangement entails many and considerable advantages, the groove on the outside making it possible to turn the cover approximately 180 degrees in relation to the appertaining back-half or, at any rate, to turn the cover through a much greater angle than if the groove in question were lacking. This will be seen most clearly from the Figures 50 5 and 6 drawn to a larger scale. The position of the cover indicated by chain-dotted lines in Fig. 6 shows how far the cover may be opened if the portion 40 is plane, whereas the position shown by full lines illustrates the corresponding extreme position of the cover when the cover attachment 15 is formed in accordance with the invention. The increased swinging path of the cover makes it 55 possible to bring the binder into the same convenient writing positions as a common book-keeping ledger or the like with a round back, if the outside of the back of the binder is arcuate or convex, as shown in the drawing. Thus all advantages of a binder with

cloth or leather hinges for the covers are maintained by the application of the present arrangement, while at the same time the invention provides for the strength and durability involved by the use of metal hinges. 70

Moreover, the embodiment of the portion 40 of the cover attachments as described involves the following objects and advantages:

(1) The construction is rendered more rigid. 75

(2) The convex inside of the portion 40 bears on the prong attachment and limits the movement of the cover when the binder is closed, the prong attachment then absorbing the pressure in the closing direction, so 80 that the binder will not be damaged even if subjected to an abnormally heavy pressure in the said direction.

(3) The convex inside of the portion 40 forms a support and bearing surface for the 85 rear edge of the cover, so that this edge cannot be damaged by the edge of the prong attachment.

By the construction of the back of the binder and of the cover attachments the further advantage is obtained against loose-leaf binders of the type in question; where the cover is secured in the outside of the cover attachment, that the book binding work is simplified very considerably, in that the card 90 board covers on the one hand and the back of the binder with the cover attachments on the other hand may be made altogether independently of each other from the beginning and may then be assembled with the greatest 95 ease by the retailer, importer and so forth.

100 Preferably, the back-halves are provided with longitudinal elevations or the like on the rear side by subjecting the sheet-metal material to a pressing operation, the said elevations or the like then serving as guide rails when the binder is taken down from its shelf or the like on which it generally rests with the back downwards. By the said arrangement the hinge between the back-halves is 105 prevented from scratching on the support of the binder. If desired, such guide rails may instead be formed by special fillets secured on the back, the same consisting preferably 110 of bakelite or fibre.

115 If desired, the hinge in the back may be countersunk inside the external plane of the back-halves.

120 Preferably, the front portions of the cover attachments are provided with rounded elevations 43 (see Fig. 7) on the outside, besides which the front edges of the back halves are bent somewhat inwardly, as at 44, Fig. 7. The object of this is to prevent scratching of the table on which the binder is placed when 125 used.

What I claim is:—

1. A loose-leaf binder comprising the combination with a pair of back members, of 130 means pivotally connecting said members for

- movement between closed and open positions, means for locking said members in closed position and in half-open position, means for releasing said locking means, said locking means preventing the movement of said back members from half-open to open position when said releasing means is active.
2. The invention set forth in claim 1 wherein said locking means comprises a latch member on one of said back members, said latch member being provided with a pair of lugs on one edge and a single lug on the opposite edge disposed intermediate said first-mentioned lugs.
3. A loose-leaf binder comprising the combination with a pair of back members, of means connecting said members for pivotal movement between closed and open positions, a recessed member on one of said back members, and a latch on the other of said back members, said latch having two lugs on one edge cooperating with the recess of said member for holding said back members in closed and half-open positions respectively and a third lug on the opposite edge cooperating with the recess of said member when said back members are in a position intermediate said closed and half-open positions to insure locking engagement of said second lug after unlatching of said first lug.
4. The invention as set forth in claim 3 wherein said back members are relatively displaceable in a longitudinal direction and said last named lug, together with said recessed member, constitute means for preventing the movement of said back members from open to closed position when said members are in any position intermediate the extreme positions of longitudinal displacement.
5. In a loose-leaf binder, the combination with a pair of back members, of means pivotally connecting said members for movement between open and closed positions, means for locking said back members in closed position and in half-open position, and means actuated upon movement of said back members from closed to open position, for operating said locking means to lock said back members in half-open position.
6. A loose-leaf binder comprising the combination with a pair of back members, of means connecting said members for pivotal relative movement between open and closed positions and for longitudinal relative displacement, and means for preventing the movement of said members from open to closed position when said members are in any position intermediate the extreme positions of longitudinal displacement.
7. A loose-leaf binder comprising the combination with a pair of back members, of means pivotally connecting the same, a pair of cover frames, and means pivotally connecting each cover frame to a back member for movement between closed and open posi-

tions, each of said cover frames having a channel adjacent the edge of its respective back member to receive the same when said cover frame is in said open position.

8. A loose-leaf binder comprising the combination with a pair of back members, of means pivotally connecting the same, a pair of covers, a frame for each cover, said frames having flanged end portions constituting supporting and protecting means for said covers, and means pivotally connecting each of said covers to a back member for movement from closed to open position, each of said cover frames being provided with a recessed portion for engagement with the edge of its respective back member when said frame is in said open position.

In testimony whereof I affix my signature.

JOSEF EINAR THURESON.
